A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a perspective view of an access control reader;

FIG. 2 is a top elevational view thereof;

FIG. 3 is a front plan view thereof;

FIG. 4 is a left side elevational view thereof;

FIG. 5 is a right side elevational view thereof;

FIG. 6 is a back plan view thereof; and,

FIG. 7 is a bottom elevational view thereof.

The broken lines shown in the drawings represent portions of the access control reader that form no part of the claimed design.
